UNITED STATES PATENT OFFICE.

WILLIAM JAMES WRIGHT, OF PITTSBURG, PENNSYLVANIA, ASSIGNOR OF ONE-HALF TO D. L. GILLESPIE, A. B. DALLY, JR., AND A. F. HOLLIDAY, OF PITTSBURG, PENNSYLVANIA.

GAS-ENGINE.

No. 915,717.

Specification of Letters Patent. Patented March 16, 1909.

Application filed December 17, 1897. Serial No. 662,277.

To all whom it may concern:

Be it known that I, WILLIAM JAMES WRIGHT, residing at Pittsburg, in the county of Allegheny and State of Pennsylvania, have invented a new and Improved Gas-Engine, of which the following is a specification.

My present invention relates to explosive engines and more particularly refers to improvements in that type of engine disclosed 10 in my co-pending application filed December 17, 1897, Ser. No. 622278.

In my other application referred to the pumping cylinder has its piston operated by an independent crank upon the crank-shaft, 15 co-operatively so arranged with the working piston crank, as to effect a suction action at predetermined times to draw off the exhaust from the back or explosion end of the working cylinder and at the same time draw in a 20 fresh charge of the working agent at the forward end of the working piston. In other words, one end of the working cylinder is charged after the other end has exploded and is exhausting, an explosion occurring at each 25 cycle of movement of the working piston in the opposite directions.

In my other application referred to, means are also provided for drawing a fresh air supply into the working cylinder in advance of a 30 new charge of the mixed air and gas of the working agent to blow out a possible flame or exploded charge portion that might remain back of the working piston, and leave the exploded end clear of burned mixture for 35 a fresh working charge.

My present invention primarily seeks to provide a modified construction of the working and pump cylinders, whereby a more economical, simplified and compact engine is produced, and in which the several parts are co-operatively so arranged that the pump will act to draw in a charge of working agent at one end of the pump cylinder by action as 40 the new charge of new working agent in front of the pump piston is being compressed so that as the working piston uncovers the exhausts for the end in which the exploded mixture is located, the new charge of working agent which has been compressed in front of the 45 pump piston will be forced into the working piston cylinder as the exploded mixture is exhausting to blow out said burned mixture.

Again, my present invention has for its object to provide means for storing up a supply of pure air which is adapted to be forced 50

into the working cylinder under considerable pressure in advance of the new charge of working agent to blow out the burned mixture before the new charge of working agent enters the working piston cylinder as the 60 working piston uncovers the exhaust ports.

With other objects in view which shall hereinafter be fully enumerated, the invention, also includes certain novel construction, combination and arrangement of parts, all of 65 which will be first described in detail and then specifically pointed out in the appended claims and illustrated in the accompanying drawings, in which:

Figure 1, is a plan view of my improved 70 gas engine, parts being in section, showing the working and pumping pistons at the extreme left hand limit of their stroke. Fig. 2, is a similar view showing the working and pumping pistons in the position they assume 75 intermediate the ends of the working and pumping cylinders and after the crank of the drive shaft has made one-fourth revolution. Fig. 3, is a transverse section on the line 3—3 of Fig. 1. Fig. 4, is a similar view on the 80 line 4—4 of Fig. 1. Figs. 5 and 6, are detail sectional views of the igniting tube device. Fig. 7, is a cross section on the line 7—7 of Fig. 1. Fig. 8, is a similar view on the line 8—8 of Fig. 1. Fig. 9, is a similar view on 85 the line 9—9 of Fig. 1.

Referring now to the accompanying drawings in which like numerals and letters of reference indicate like parts in all of the figures, the working cylinder 1, and the 90 pump cylinder 2 are arranged in the same longitudinal alignment, the working and pumping pistons X and Y respectively of the working and pumping cylinders 1 and 2 respectively, being connected together by the 95 rod 3 so that the two pistons will move in unison.

At each end the working cylinder 1 has a duplex set of igniting tubes 4 and 5, of different heat area, the larger ones 5, of which, are brought into use only when it is desired to explode a charge at the end of the working cylinder 1, to start the engine from a stopped or dead position, the smaller tubes 4, being used after the engine has started and during the regular running thereof. Each set of igniting tubes has a rotary valve mechanism 6 having ports 6^a—6^b so arranged with respect to the igniting tubes that when the valve 6 is set in one position, the short ignit- 100 105 110

ing tubes 4 will be in an operative condition, see Figs. 5 and 6, and when turned to a second position so that the port 6^b will communicate with the ignition tube 5, the valves 6 will cut out the short tubes 4 and place the long tubes 5 in operative communication with the interior of the working cylinder. Each valve 6 has a suitable handle 6^a for manipulating the same, it being understood that the ports 6^a—6^b are so arranged that when the valves are set with the ports 6^a—6^b between the tubes 4 and 5, both tubes 4 and 5 will be cut out and the engine stopped.

The left hand end of the working cylinder 1 is connected to the right hand end of the pump cylinder 2 by a pipe 7 while the right hand end of the working cylinder 1, and the left-hand end of the cylinder 2 communicate with each other through the pipe 8, which pipe 8 is made of sufficient convolutions to have the same capacity as the pipe 7.

At the points where the pipes 7 and 8 join with the working cylinder 1, they are provided with back pressure valves 7^a—8^a (see Figs. 1, 2, 8 and 9), and they also have each a supplemental chamber 7^b—8^b respectively in which the valves 9—9^x for closing off the chamber 7^b—8^b respectively from the chambers 9^a—9^b respectively into which the pipes 7 and 8 lead, the valves 9—9^x opening one way into the chambers 9^a—9^b to chamber 7^b—8^b respectively while the valves 7^a—8^a open outwardly from the chambers 9^a—9^b into the working cylinder.

10—10 denote fresh air supply pipes each provided with a check valve 10^a, as shown. These pipes 10—10 connect with the main feed pipe 10^b which connects with a valve mechanism V, in a manner presently explained, and the said pipes 10—10 communicate with the chambers 7^b and 8^b, as shown by dotted lines in Figs. 8 and 9.

V designates a double acting valve mechanism comprising a valve casing 11^a having a valve chamber 11^c in which a valve member 15 is slidable and this valve member 15 is of tubular form and provided with ports 15^a—15^b—15^c respectively. The valve casing 11^a is provided with a pair of diametrically opposite alining ports 11^b—11^c with which the air supply pipe 11 and the air off-take pipe 13 respectively connect, the valve member 15 being so arranged that when the valve is moved in the position shown in Fig. 2, the ports 15^a and 15^b open up communication between the air pipe 11 and the off take pipe 13 and when the valve member 15 is in the position shown in Fig. 1, the port 15^a is out of communication with the port 13 although the port 15^b is still partially in communication with the pipe 11. The port 15^c of the valve casing 11^a, is adapted, when the valve is in the position shown in Fig. 1, to register with an aperture 11^d in the valve casing 11^a into which the

feed pipe 10^b is led. When the valve is in the position shown in Fig. 2, the pipe 10^b is cut out. The valve mechanism V also comprises an air chamber or pocket 14 closed by a flexible diaphragm 14^a to which the stem 15^x of the valve member 15 is secured.

The valve stem 15^x projects through the diaphragm 14^a and into a supplemental valve casing 12^x having a chamber 12^a in which a slide valve 16 is movable and the valve 16 has a port 16^a for opening up communication with the apertures 12^b—12^c of the valve casing 12^x into which apertures 12^b—12^c, the gas supply pipe 12 and the gas off-take pipe 12^y respectively lead. The slide valve 16 and the valve member 15 are so arranged that when the valve member 15 is in the position shown in Fig. 1, the pipes 12—12^y are out of communication with each other, and when the valve mechanism is in the position shown in Fig. 2, the pipes 12 and 12^y are in communication with each other. The air off-take pipe 13 and the gas off-take pipe 12^y connect together through the lead 13^x with the pipe 13^y whose ends communicate with the right and left hand ends respectively of the pumping cylinder 2 and the said pipe 13^y is provided with check valves 13^a—13^b and cut-off valves 13^b—13^c as clearly shown in Figs. 1 and 2 of the drawings.

The cylinder 1, at points intermediate the center and ends, has two sets of escape ports 17 that open into an annular jacket 17^a which discharges into an off-take 17^b to the atmosphere.

Operation: Assuming the parts to be in the position shown in Fig. 1 a compressed working charge in the left hand end of the working cylinder just about to be exploded, the pipe 7 filled with air, the right hand end of the working cylinder having the burned mixture exhausted and just about filled with new working agent, the pipe 8 and the remaining space in the left hand end of the pumping cylinder being filled with working agent and valve V being in the position shown; as the charge at the left hand end of the working cylinder is exploded and the pistons moved in the direction indicated by the arrow, the valve 7^a will be held closed, due to the pressure of the exploded charge in the left hand end of the cylinder, the valve 9^a at the left hand end of the working cylinder will be closed due to the pressure in the pipe 7 which increases as the pumping piston moves in the direction of the arrow to compress the working agent in the right hand end of the pumping cylinder. Now as the pistons begin their movement in the direction of the arrows in Fig. 1, the working piston X will close the right hand set of exhaust ports 17, and compress the charge of working agent within the right hand end of the working cylinder, it being understood, that as

At this compression in the right hand end of the working cylinder begins, the valve 8^a will be held closed by the pressure of the working agent in the right hand end of the working cylinder. As the pump piston Y begins its movement from left to right in the direction of the arrow, it cannot draw in new working agent through the pipe 13^y as the valve member 15 is shifted to hold the pipe 13 out of communication with the air pipe 11 as shown in Fig. 1, therefore the pump piston Y will draw the working agent out of the pipe 8 into the left hand end of the pump cylinder thus causing valve 9^a to open up and allow air to be drawn into pipe 8 through pipes 10—10^b as the pipe 10^b is in communication with the pipe 11 through the ports 15^b—15^c. The beginning of the movement of the pistons from left to right is a quick one and by the time piston Y has drawn the working agent which was formerly in pipe 8 out of the same and drawn sufficient air into the pipe 8 to fill the same, the suction created by the air passing through pipe 11 into pipe 10^b causes a partial vacuum in the chamber 14 which shifts the valve member 15 to the position shown in Fig. 2. After the valve has been shifted to the position shown in Fig. 2, which occurs just as soon as the pipe 8 has become filled with air, then the piston Y can no longer draw air into the pipe 8 through the pipe 10—10^b as the pipe 10^b is cut off from the air pipe 11. The pipe 8 remains full of air during the rest of the suction stroke of the pump, since the suction created by such stroke draws air and gas through pipes 11, 13, 12 and 12^y into the left hand end of the pumping cylinder, it being understood that at this time pipes 12 and 12^y and 11 and 13 respectively, are in communication with each other. As the pistons reach the limit of their stroke in the direction indicated by the arrows in Figs. 1 and 2, the working agent in the right hand end of the pump pistons will have been compressed to its full extent while an uncompressed charge of working agent will have been drawn into the left hand end of the pump cylinder. At the same time the working agent in the right hand end of the working cylinder will have been compressed while the exploded mixture in the left hand end of the cylinder will have moved the piston in the direction indicated by the arrow and spent its force. As the pistons reach the limit of their stroke in the direction of the arrow, the left hand series of exhaust ports 17 of the working cylinder will be uncovered, thus allowing the exploded charge to pass out into the exhaust receiver and from thence to atmosphere, and as soon as the exhaust ports 17 are open at the left hand end of the cylinder, the valve 7^a will open due to the difference in pressure between the exploded working agent at the left hand end of the working cylinder which

is at practically atmospheric pressure and the compressed air in pipe 7 and compressed working agent charge in right hand end of the pumping cylinder. As valve 7^a opens, the compressed charge in the right hand end of the pumping cylinder will force the air out of the pipe 7 into the left hand end of the working cylinder which air of the pipe 7, in turn, forces out the exploded mixture from the left hand end of the working cylinder to atmosphere; the air from the pipe 7 being then forced out of the left hand end of the working cylinder by the compressed charge of new working agent from the right hand end of the pumping cylinder, it being understood that the pistons X and Y do not start on their return stroke in a direction opposite to the arrows in Figs. 1 and 2, and cover up the left hand series of ports 17 of the working cylinder, until the compressed charge of working agent in the right hand end of the pumping cylinder has forced the air out of pipe 7 into the left hand end of the working cylinder and out of said end of the working cylinder into the exhaust receiver. As soon as this is done and the left hand end of the working cylinder has become filled with a new charge, the pistons X and Y begin their movement from right to left in the direction opposite to the arrows in Figs. 1 and 2 to compress the charge of working agent into the left hand end of the working cylinder as the pistons are moved from right to left due to the charge on the right hand end of the working cylinder which is exploded as soon as the pistons start on their return stroke from right to left. It should be understood that as soon as the pistons reach the limit of their stroke in either direction, there is a momentary stoppage of both pistons when no movement thereof takes place. At this instant, the vacuum in the chamber 14 is released and the flexible diaphragm together with the spring of the valve V shifts the valve V into the position shown in Fig. 1. Now as the piston begins to move from right to left to compress the charge in the left hand end of the working cylinder, (the charge in the right hand end of the working cylinder being just exploded) the valve 8^a is held closed, valve 9^a is also held closed, valve 7^a is held closed while valve 9 opens to allow the piston Y at the beginning of its movement from right to left to draw in air from pipe 11 through pipes 10^b—10 into the pipe 7 to fill the same, it being understood that as soon as the pipe 7 is filled the vacuum created in the chamber 14 of the valve V will again cause the valve V to shift to cut off pipe 10^b and open up communication between pipes 11, 13, 12, 12^y and 13^y to allow the pump piston during the remainder of its stroke from right to left to draw in a fresh working charge into the right hand end of the pump-

4
ing cylinder. As the piston Y moves from right to left the charge in the left hand end of both cylinders will be compressed as before. As the pistons reach their initial position the same series of operations take place, as before.

From the foregoing description taken in connection with the accompanying drawings, it is thought the complete construction, 10 operation and many advantages of my invention will be apparent to those skilled in the art to which it appertains.

Having thus described my invention, what I claim and desire to secure by Letters Patent, is:—

1. A gas engine comprising a working cylinder having inlet ports at its opposite ends and exhaust ports intermediate the ends, a pumping mechanism for compressing a new 20 charge while the working piston is making its stroke effected by the impulse of the last exploded mixture, pipe connections of relatively small cross sectional area and great length, between the pumping mechanism 25 and the working cylinder for storing up air, air admitting means connected with said pipe connections, said pump arranged to force said air out of the pipe connections into the working cylinder in advance of the 30 new charge of working agent substantially as shown and described.

2. A gas engine comprising a working cylinder and a piston reciprocably mounted therein, inlet ports at each end of said working cylinder, two sets of exhaust ports intermediate the ends and middle of said working cylinder; a pump comprising a pumping cylinder and pumping piston reciprocably mounted therein, said working and pumping 40 pistons being connected to move in unison, a storage and connecting pipe connecting one end of the working cylinder to the opposite end of the pumping cylinder, a check valve adjacent the working cylinder for said storage and connecting pipe, a second storage and connecting pipe joining the other end of the working cylinder to the other end of the pumping cylinder, a valve device adjacent the working cylinder for said second 45 storage and connecting pipe, valve controlled air pipes connecting with said storage and connecting pipes at the ends adjacent the working cylinder, an air supply and a gas supply pipe, a double acting valve connected with said air and gas supply pipes and with said air pipe which connects with the storage pipes, a pipe having laterals connected with each end of the pumping cylinder and connected to said double acting 50 valve, said double acting valve having provisions in virtue of which communication may be had between the air inlet pipe and the air supply pipe for the storing and connecting pipes or communication may be had 55 between the air supply pipe and the pipe

connecting with the pump cylinder and between the gas supply pipe and the pipe connecting with the pump cylinder while simultaneously cutting off the air supply to the air pipe which connects with the said storing 70 and connecting pipes, all being arranged substantially as shown and described.

3. A gas engine comprising a working cylinder having inlet ports at its opposite ends and exhaust ports intermediate the ends, a pumping mechanism, pipe connections of relatively small cross sectional area and great length, between the pumping mechanism and the inlet ports of the working cylinder, said pumping mechanism having provisions for compressing a new charge while the working piston is making its stroke effected by the impulse of the last exploded mixture and for storing up air in such pipe connection, said pump arranged to force 80 such air out of said pipe connection into said working cylinder to blow out the exploded mixture and to force the compressed new charge into the working cylinder after the air, substantially as shown and described. 85

4. A gas engine comprising a working cylinder having inlet ports at its opposite ends and exhaust ports intermediate the ends, a pumping mechanism, pipe connections of relatively small cross sectional area 90 and great length, between the pumping mechanism and the inlet ports of the working cylinder, said pumping mechanism having provisions for compressing a new charge while the working piston is making its stroke 95 effected by the impulse of the last exploded mixture and for storing up air in such pipe connection, said pump arranged to force such air out of said pipe connection into said working cylinder to blow out the exploded mixture and to force the compressed new charge into the working cylinder after the air, to force out the air and refill the working chamber with a fresh charge substantially as shown and described. 100

5. A gas engine comprising a working cylinder having inlet ports at its opposite ends and piston controlled ports intermediate the ends, a pumping mechanism, pipe connections between the pumping mechanism and the inlet ports of the working cylinder, said pipe connections being relatively long and of small cross sectional area to serve as air storing reservoirs, means controlled by the pumping mechanism for drawing in working agent into the pumping mechanism, means for automatically shutting off the air supply to the pipe connections when they are filled with air, said pumping mechanism arranged to force said air within the pipe connections 115 into the working cylinder in advance of the new working charge to blow out the exploded mixture before refilling the working chamber with fresh charge, substantially as shown and described. 120

6. A gas engine comprising a working cylinder having inlet ports at opposite ends, and piston controlled exhaust ports intermediate the ends, a pumping mechanism co-operating with said working cylinder, pipe connections of relatively great length and small cross sectional area between the pumping mechanism and the inlet ports of the working cylinders, valve controlled working agent inlet ports for said pumping mechanism having provisions for compressing a new charge while the working piston is making its stroke effected by the impulse of the last exploded mixture and for storing up air in said pipe connections, said pumping mechanism arranged to force said air from said pipe connections into said working cylinder to blow out the exploded mixture, and to force the compressed new charge into the working cylinder after the air, to refill the working chamber with a fresh charge, substantially as shown and described.

7. A gas engine comprising a power cylinder having induction ports at its opposite ends and centrally disposed exhausts, of a pump connected with the working cylinder for storing up and compressing a new charge outside of said working cylinder as a charge within the working cylinder is being compressed, valved cut-offs governed by the discharge of the exhaust in the working cylinder for opening up communication between the pump and the working cylinders whereby to admit of the exteriorly held compressed charge into the working cylinder after the previous charge has become exhausted, said connections between the pump and working cylinders serving as fresh air reservoirs, substantially as shown and described.

8. An explosive engine, comprising a working cylinder and a pump cylinder arranged in tandem, a single piston rod, having a piston operating in the working cylinder and a piston operating in the pumping cylinder, the adjacent ends of the two cylinders having a pipe connection, a closure valve in said connection, the other ends of the two cylinders having a like valved connection, a working agent feed pipe having valved laterals connecting with the opposite ends of the pumping cylinder and a separate fresh air supply connected with each end of the working cylinder and automatically governed valve devices for opening up the said air supply directly against the exploded charge prior to feeding in a new charge of working agent as specified.

9. In an explosive engine as described, the combination with the working and pump cylinders, co-operating pistons X and Y, and the valved connections for bringing the opposite ends of the two cylinders into communication with each other; of a working agent

feed connected with the pump cylinder, a fresh air supply for each end of the working cylinder, valved ports through which said air supply passes into the working cylinder, a valve device for controlling the feed of air and gas to the pump cylinder, said device including means for cutting off the aforesaid fresh air supply to the working cylinder when the working agent is fed therein, as set forth.

10. The combination with a power cylinder having inlet ports and piston controlled exhaust ports, of a pumping mechanism for forcing charges of working agent into the power cylinder as it is being relieved of the exploded mixture, pipe connections of relatively great length and small cross sectional area between the pumping mechanism and the power cylinder to permit passage of working agent and scavenging agent from the pumping mechanism to the power cylinder, and air and working agent feed mechanism for the pumping mechanism, an automatic controlling means for said air and working agent feed mechanism, said pipe connections serving as fresh air reservoirs, said pumping mechanism serving to force a new charge of working agent into the fresh air reservoir to displace the fresh air and force it into the power cylinder to blow out the burned mixture before the new charge enters the power cylinder and serving to refill the air reservoir at times, said air and working agent feed controlling means having provisions for cutting off the pure air supply and admitting combined air and working agent into the pumping cylinder at times, substantially as shown and described.

11. A gas engine comprising in combination with a power cylinder having inlet ports at its opposite ends and piston controlled exhaust ports intermediate its ends, of a pumping mechanism, connections of relatively great length and small cross sectional area, between the pumping mechanism and the inlet ports of the power cylinder, said connections forming a fresh air reservoir, valve controlled working agent inlets for said pumping mechanism, valve controlled air inlets for said fresh air storing reservoir, said pumping mechanism operating to draw in fresh air into said fresh air storing reservoir and to force said fresh air from said reservoir into said power cylinder after the exhaust ports thereof are opened to blow out the burned mixture and serving to force a new charge of working agent through said reservoir into said power cylinder to displace the fresh air, substantially as shown and described.

12. In a gas engine, the combination with a power cylinder having inlet and exhaust ports, of a pumping mechanism, connections between the pumping mechanism and the power cylinder, means for first drawing in a fresh air charge into said connections and

then drawing in a charge of working agent into said pumping mechanism, and then forcing said charge of working agent from the pumping mechanism to displace the fresh air charge and force it into the power cylinder when the exhaust ports thereof are open to cause the fresh air charge to blow out the

burned mixture as the new charge of working agent reaches the power cylinder, substantially as shown and described.

WILLIAM JAMES WRIGHT.
